US00D795371S

(12) **United States Design Patent** (10) Patent No.: **US D795,371 S**
(45) Date of Patent: **** Aug. 22, 2017**

(54) **GOLF CLUB HOSEL INSERT**

(71) Applicant: **KARSTEN MANUFACTURING CORPORATION**, Phoenix, AZ (US)

(72) Inventors: **Ryan M. Stokke**, Anthem, AZ (US);
Jacob Clarke, Phoenix, AZ (US)

(73) Assignee: **Karsten Manufacturing Corporation**,
Phoenix, AZ (US)

(**) Term: **15 Years**

(21) Appl. No.: **29/563,121**

(22) Filed: **May 2, 2016**

Related U.S. Application Data

(60) Division of application No. 29/515,574, filed on Jan. 23, 2015, now Pat. No. Des. 757,194, which is a continuation-in-part of application No. 14/593,963, filed on Jan. 9, 2015, which is a division of application No. 13/468,675, filed on May 10, 2012, now Pat. No. 8,932,147, which is a continuation-in-part of application No. 13/429,319, filed on Mar. 24, 2012, now Pat. No. 8,790,191.

(57) **CLAIM**

The ornamental design for a golf club hosel insert, as shown and described.

DESCRIPTION

FIG. 1 is a top perspective view of a golf club hosel insert; FIG. 2 is a bottom perspective view of the golf club hosel insert of FIG. 1;

FIG. 3 is a front view of the golf club hosel insert of FIG. 1;

FIG. 4 is a rear view of the golf club hosel insert of FIG. 1; FIG. 5 is a top view of the golf club hosel insert of FIG. 1; FIG. 6 is a bottom view of the golf club hosel insert of FIG. 1;

FIG. 7 is a left view of the golf club hosel insert of FIG. 1; and, FIG. 8 is a right view of the golf club hosel insert of FIG. 1.

The broken lines connecting the solid contour lines represent the bounds of the claim. The remaining broken lines illustrate the environment. None of the broken lines forms part of the claimed design.

1 Claim, 3 Drawing Sheets
